UNITED STATES PATENT OFFICE.

PAUL H. WELCKER, OF ST. PAUL, MINNESOTA, ASSIGNOR TO BROWN & BIGELOW, OF ST. PAUL, MINNESOTA, A CORPORATION OF MINNESOTA.

CALENDAR.

Application filed May 14, 1920. Serial No. 381,306.

To all whom it may concern:

Be it known that I, PAUL H. WELCKER, a citizen of the United States, residing at St. Paul, in the county of Ramsey and State of Minnesota, have invented a new and useful Improvement in Calendars, of which the following is a specification.

My invention relates to improvements in calendars designed for use for any year to indicate the days of the month by a simple, effective design, which gives a perpetual calendar with a neat and attractive appearance.

The invention further provides means which allow the calendar pad to be freely removed so that it can be reversed and thus either side of the pad carries figures indicating the days in the month in large, clear numerals, which can be readily distinguished from a distance. The calendar pad is adapted to indicate each day separately and by using both sides of the leaves of the pad the number of leaves required for the same is reduced. This reduces the cost of the calendar, gives a neat appearance and provides a practical device.

It is also a feature of the invention to provide a convenient means for illustrating the name of the day and the month arranged so as to be readily associated with the number of the day, whereby one can tell the day and month of the year by a glance at the calendar. The free attaching of a pad to the calendar body allows the pad to be changed each day, but the construction is so arranged that while the pad hangs freely removable in displayed position it will not be accidentally removed or misplaced.

The invention further comprehends rotatable, concentric means for illustrating the day and month, while suitable means are provided for spacing the rotatable means apart and for holding the day displaying means separate and independently operable in relation to the month displaying means. Thus either can be operated independently and without affecting the other.

In the drawings forming part of this specification:

Figure 1 is a front elevation of the calendar as it would appear in use.

Figure 2 is a side elevation of the calendar.

Figure 3 is a front elevation of a portion of the calendar, illustrating the daily pad removed.

Figure 4 is a perspective view of one of the pad holding brackets.

Figure 5 is a section on the line 5—5 of Figure 3.

Figure 6 is a back view of the front of the calendar on the line 6—6 of Figure 5.

Figure 7 is a front view of the back of the calendar as indicated by the line 7—7 of Figure 5.

The calendar A is formed with a front portion 10, formed of metal or other suitable material, having beveled surfaces 11, while the edges 12 of the front are folded back from the beveled surfaces 11 to engage and secure the back 13 thereto. The back 13 is formed of cardboard or other suitable material and is held against the inner surface of the beveled faces 11 so that the front 10 and back 13 are held spaced apart from each other.

In the compartment formed by the space between the front 10 and the back 13 of the calendar A, in the lower portion thereof, are positioned rotatable, concentric disks 14 and 15, formed of metal or other suitable material. The disk 14 is secured by the eyelet 16 to the front 10, and the transversely extending spacing member 17, which extends across between the sides of the front and back member of the calendar A and is rigidly connected on its ends thereto. The disk 14 carries the names of the months of the year, which are visible through the opening 18 in the front face 10 of the calendar A. Indents 19 are formed in the front face 10 of the calendar A, which engage the surface of the disk 14 to space the same away from the inner surface of the front 10 so as to prevent the disk from scraping thereon when it is rotated, which would have a tendency to mar the surface carrying the display of the months when the disk 14 is rotated.

The disk 14 is provided with openings 20, which can be engaged through the slot 21 formed in the front face of the calendar A by a suitable instrument to rotate the disk 14 from one month to the other to display the month of the year through the opening 18.

Concentric with the disk 14, the disk 15

is secured to the back 13 of the calendar and is adapted to carry the days of the week printed thereon so as to display the same through the opening 22 formed in the front 5 face 10 of the calendar A directly above the opening 18. The disk 15 is spaced away from rubbing on the surface of the back of the disk 14 by indents 23 formed projecting from the back of the spacing member 17 and these indents are also adapted 10 to assist in holding the disk 15, which is somewhat larger than the disk 14, against any unnecessary play between the sides 10 and 13 of the calendar. Both of the disks 15 15 and 14 are freely rotatable but are held with sufficient friction to prevent them from accidentally rotating when it is not desired. The disk 15 is provided with openings 24, which are engaged through the slot 25 20 formed in the front face 10 of the body of the calendar A, as illustrated in Figure 3, and by engaging one of the openings 24 and moving it the length of the slot 25 the day of the week can be changed to illustrate 25 and display the desired day of the week through the opening 22 of the calendar A, as illustrated in Figures 1 and 3. The disk 15 is secured to the back 13 by the eyelet 26.

To protect the back 13 from engagement 30 with the instrument engaging in the openings 24, especially when the back 14 is formed with cardboard, a metallic plate or guard 27 is positioned back of, and is formed with a portion which projects beneath the lower portion of the disk 15 so that in the movement of the disk 15 by an instrument engaging in the openings 24, the operating instrument will engage against the surface of the guard 27 and thus will not injure or harm the cardboard back 13. Suitable spacing and filling blocks 28 can be attached to the back 13 to properly fill and space the disk 15 in the compartment between the front and back of the calendar A.

40 Angular brackets 29, having supporting arms 30, are attached to the inner surface of the front 10, the arm 30 extending through the slots 31 in the front, while the enlarged body portion 32 of the bracket is 45 attached by a rivet 33, or other suitable means, to the front 10 to rigidly attach the supporting brackets with their arms 30 projecting from the outer face of the same.

A portion 34 of the arm 30 extends perpendicular from the face 10 of the calendar A, while a portion 35 is bent at right angles to the portion 34 so that the portion 35 extends approximately parallel with the front face 10.

50 The portion 35 is formed with a perpendicular slot 36, in which the rings 37 of the daily pad B are adapted to engage. The pad B is made up of a series of leaves 38, on which are printed or otherwise displayed 55 numerals to indicate the number of the day

of the month. The leaves 38 carry numerals on both sides thereof, thus materially reducing the number of leaves required for the pad B. The rings 37 hold the pad B by engagement with the openings 39 formed in each of the leaves 38 and the rings 37 are freely removable from the slots 36 so that each day the calendar can be changed to the next consecutive numeral to indicate the day of the month and year, while by engaging the disk 15 the name of the day can be changed to indicate the time of the year, while the disk 14 indicates the month.

The pad B hangs freely from the bracket arms 30 and is adapted to cover the slots 21 and 25 so that the calendar will have a neat and tidy appearance, displaying the day, month and the number of the day in large, clear numerals, which can be readily seen from a distance. When it is desired the leaves 38 can be made of metal and the numerals enameled thereupon, while the rest of the calendar and particularly the front 10 with the display on the disks 14 and 15 can also be enameled in any suitable manner to make a very attractive and pleasing calendar.

It is very desirable to have the pad B freely removable from the supporting arms 30 and the construction illustrated gives an inexpensive, practical device. The deep recess 36 in the arm 30 prevents the calendar pad B from being accidentally disengaged from the arms 30 and yet allows the same to be freely removed to change the daily pad. This construction provides a perpetual calendar without any complicated mechanism which might possibly get out of order and gives a design of calendar which is very pleasing and attractive.

In accordance with the patent statutes I have described the principles of operation of my invention, together with the apparatus which I now consider to represent the best embodiment thereof, but I desire to have it understood that the construction shown is only illustrative and that the invention can be carried out by other means and applied to uses other than those above set forth within the scope of the following claims:

1. A calendar, including a body portion, a month day pad, including a series of sheets having numerals on either side thereof brackets for supporting said pad and rings for collectively and detachably holding said pad to said bracket on said body portion.

2. A calendar, including a body portion, a day pad, comprising a series of sheets having numerals to indicate one day on each side thereof, rings adapted to collectively hold said leaves together and supporting brackets secured to said calendar adapted to hold said rings to removably position said day pad to the body of said calendar.

3. A calendar having a body portion, a pair of angular supporting brackets projecting from said body portion, the free ends of said brackets projecting toward each other, open recesses formed in said brackets, a day pad, including a plurality of sheets having numerals printed on each side thereof, a pair of rings for holding said sheets collectively, said rings being adapted to engage in said open slots in said brackets to freely and removably support said day pad from said brackets.
4. A calendar including a body portion, arms projecting from said body portion having ends extending parallel to said body

portion, a day pad, and rings adapted to hold said day pad collectively and to directly engage the ends of said arms.

5. A calendar including a body portion formed with front and back members spaced apart, concentric display disks positioned in said body portion between said front and back members, said disks being separately mounted from each other on the front and back members of said calendar, separate display and operating openings for said disks in the front member of said calendar, and a daily pad adapted to normally conceal the operating openings in the front member.

PAUL H. WELCKER.
